GOLF CLUB HEAD

Dan D. Bizovi, 8171 New Bradford Drive,
Sterling Heights, Mich. 48077

Filed Oct. 24, 1974, Ser. No. 517,478

Term of patent 14 years

Int. Cl. D21—02

U.S. Cl. D34—5 GH

FIG. 1 is a side elevational view of a golf club head showing my new design;

FIG. 2 is a top plan view thereof;

FIG. 3 is a front elevational view taken from the right of FIG. 1;

FIG. 4 is a side elevational view of the side opposite that shown in FIG. 1;

FIG. 5 is a rear elevational view; and

FIG. 6 is a bottom plan view.

I claim:

The ornamental design for a golf club head, substantially as shown.
